(57) **CLAIM**

The ornamental design for an exercise ball platform as shown and described.

DESCRIPTION

FIG. 1 is a bottom perspective view of the exercise ball platform showing the claimed design;

FIG. 2 is a top perspective view of the exercise ball platform shown in FIG. 1;

FIG. 3 is a bottom plan view of the exercise ball platform shown in FIG. 1;

FIG. 4 is a top plan view of the exercise ball platform as shown in FIG. 1;

FIG. 5 is a front elevational view of the exercise ball platform shown in FIG. 1, the back elevational view being a mirror image of the front elevational view; and,

FIG. 6 is a left-side elevational view of the exercise ball platform shown in FIG. 1, the right-side elevational view being a mirror image of the left-side elevational view.

The broken lines in the figures show portions of the design that form no part of the claimed design.

1 Claim, 6 Drawing Sheets
